TO HEALD MACHINE COMPANY, OF WORCESTER, MASSACHUSETTS, A CORPORATION
OF MASSACHUSETTS.

WHEEL-GUARD.

1,250,168.

Specification of Letters Patent. Patented Dec. 18, 1917.

Application filed September 6, 1917. Serial No. 189,905.

To all whom it may concern:

Be it known that we, JAMES N. HEALD and ALDEN M. DRAKE, citizens of the United States, residing at Worcester, in the county of Worcester and State of Massachusetts, have invented a new and useful Wheel-Guard, of which the following is a specification.

This invention relates to a wheel guard, particularly designed for use on grinding machines though capable of more general application.

In certain types of grinding machines, and particularly in internal grinding machines, it is impossible to use a wheel guard which is fixed in relation to the grinding wheel, because of the necessary forward movement of the wheel inside of the work. It has been found, however, that accidents sometimes occur on such machines, particularly during the operation of gaging or testing the size of the hole last ground, after the wheel has been withdrawn therefrom.

Such accidents are caused by the sticking of the gage in the hole, followed by its abrupt release when special force is applied thereto. The hand or arm of the operator is thus forced backward against the rapidly revolving wheel.

It is the object of our invention to provide a wheel guard which is normally in inoperative position, but which will be moved to operative position upon the withdrawal of the wheel from the work. We have shown our invention as embodied in an internal grinding machine in which the work head and the wheel head are relatively movable to advance and withdraw the wheel from the work. An important feature of our invention relates to the provision of suitable connections by which the guard is advanced to operative position to cover the wheel upon a relative movement of separation of the wheel and work heads. We have also provided means for normally retaining the wheel guard in inoperative position, and means permitting a further movement of separation of the heads after the guard is in operative position.

Our invention further relates to arrangements and combinations of parts which will be hereinafter described and more particularly pointed out in the appended claims.

A preferred form of our invention is shown in the drawings, in which— 55

Figure 1 is a plan view of an internal grinding machine embodying our invention;

Fig. 2 is a similar plan view, with the parts in grinding position;

Fig. 3 is a front elevation of the machine; 60

Fig. 4 is a detail plan view of the wheel guard;

Fig. 5 is a sectional elevation on the line 5—5 of Fig. 4, and

Fig. 6 is a plan view of a chain-holding 65 plate.

Referring to the drawings, we have shown our invention embodied in an internal grinding machine of a common type, having a frame 10, a fixed work-supporting head 11, 70 a movable wheel head 12, and an internal grinding wheel W. The wheel head 12 is mounted on a cross-slide 13 movable transversely upon a table or base slide 14 which in turn is movable longitudinally on the 75 frame 10 of the machine.

My improved wheel guard comprises a guard or plate 20 angularly and longitudinally adjustable upon a rod 21 which in turn is both angularly and longitudinally adjustable in the arm 22 of a bell-crank which is pivoted upon a stud 23 fixed in the cross-slide 13. The bell-crank is held in vertical position between collars 24 and 25 on the stud 23. A coil spring 26 encircles the hub 85 of the bell-crank, one end of the spring being secured to said hub, and the other end of the spring engaging a stud 27, fixed in the slide 13. The collar 24 is pinned to the bell crank and is provided with lugs 24^a which 90 engage the stud 27 and limit the movement of the bell crank and wheel guard in both directions.

The second arm 28 of the bell-crank is connected by a spring 29 and a chain 30 to a 95 slotted plate 31 (Figs. 1 and 6) fixed to the work head 11. The spring 26 is so disposed that it normally moves the arm 22 and guard 20 to inoperative position. When, however, the wheel head is withdrawn or separated 100 from the work head, the chain 30 and spring 29 will be tensioned until the guard 20 is thrown into position in front of the grinding wheel, which is thereby protected so as to prevent accidental contact therewith. If the 105 movement of separation is more than suf-

ficient to bring the wheel guard to operative position, the spring 29 will stretch to permit of the additional movement.

We have thus provided an extremely simple wheel guard which is automatically advanced to operative position whenever the wheel is moved to a position in which it may be dangerous to the operator. As the wheel is again advanced toward the work, the spring 26 is permitted to operate to remove the guard from operative position.

Having thus described our invention, it will be evident that changes and modifications can be made therein by those skilled in the art without departing from the spirit and scope of our invention as set forth in the claims, and we do not wish to be otherwise limited to the details herein disclosed, but what we claim is:—

20 1. In a grinding machine, in combination, relatively movable wheel and work heads, a wheel guard, means to hold said guard normally in inoperative position, and means to move said guard to operative position upon relative separation of said heads.

2. In a grinding machine, in combination, a grinding wheel, relatively separable wheel and work supports, a normally inoperative wheel guard mounted on the wheel support, 30 and means effective to move said guard to operative position as the wheel and work supports are relatively separated.

3. In a grinding machine, in combination, relatively separable wheel and work heads, 35 a guard mounted on the wheel head, and a connection from said guard to said work head effective to move said guard to operative position as the heads are relatively separated.

40 4. In a grinding machine, in combination, relatively movable wheel and work heads, a wheel guard, an arm supporting said guard and pivoted to said wheel head, and means to swing said arm and guard to operative 45 position upon relative separation of said heads.

5. In a grinding machine, a wheel head, a wheel rotatably mounted thereon, a guard, a spring normally holding said guard in inoperative position, and means to advance 60 said guard to operative position as the wheel is withdrawn from the work.

6. In a grinding machine, a grinding wheel, a wheel head, a guard mounted on said head movable horizontally to operative 65 and inoperative positions, a spring effective to swing said guard normally to inoperative position, a member movable relatively to said wheel head as the wheel and work are separated, and a connection from said member to said guard, effective to move said guard to operative position on such relative separation of wheel and work.

7. In a grinding machine, a grinding wheel, a wheel head, a guard mounted on 65 said head movable horizontally to operative and inoperative positions, a spring effective to swing said guard normally to inoperative position, a member movable relatively to said wheel head as the wheel is being withdrawn from the work, a connection from said member to said guard, effective to move said guard to operative position, on such relative movement of said wheel and member, and means permitting further relative 70 movement of said member after said guard is operatively positioned.

8. In a grinding machine, a grinding wheel, a wheel head, a guard mounted on 80 said head movable horizontally to operative and inoperative positions, a spring effective to swing said guard normally to inoperative position, a connection to said guard effective to move said guard to operative position on relative separation of the wheel and work, 85 and a spring in said connection adapted to yield upon further separation of said parts after said guard is operatively positioned.

In testimony whereof we have hereunto affixed our signatures.

JAMES N. HEALD.
ALDEN M. DRAKE.
